DISPENSING DEVICE

Filed Feb. 7, 1929

INVENTOR
ARTHUR S. HOOD

By *John Ellis*

ATTORNEY

UNITED STATES PATENT OFFICE

ARTHUR S. HOOD, OF KENMORE, NEW YORK

DISPENSING DEVICE

Application filed February 7, 1929. Serial No. 338,269.

My invention relates in general to dispensing devices, and more particularly to a measuring and dispensing device for handling ice cream, ices, and similar delicacies.

5 The principal object of my invention has been to provide a predetermined measuring device which is very convenient to manipulate and accurate in its measurement.

Another object has been to provide a device 10 of this nature which shall be adjustable so that the measuring capacity may be accurately predetermined.

Moreover, my device is provided with a knife which serves to effectively cut off the 15 ice cream at the bottom of the device when such commodity is being taken from the container.

Furthermore, my device is provided with means for increasing the frictional contact 20 of the ice cream with the parts of the device so that the ice cream even if in a soft condition will be retained in place, and, therefore, accurately measured.

Moreover, my device is simple and inexpensive to manufacture; easy to operate; and easy to keep clean.

The above objects and advantages have been accomplished by the device shown in the accompanying drawings, of which:

30 Fig. 1 shows a side, sectional elevation of my complete device, taken on line 1—1 of Fig. 2.

Fig. 2 is a bottom view of the complete device.

35 Figure 3 is a side elevation of the device with portions thereof broken away.

My device comprises a measuring cup or cylinder 5 which is of a desired size and provided with a lower edge 6, which is preferably chamfered from the outside toward the inside of the cylinder, thus providing a relatively sharp edge which will very easily penetrate the ice cream, ice, or other delicacy being handled. The cylinder is carried by

40 a hollow sleeve 7 and is secured to this sleeve by means of a top plate 8. This plate, as shown in dotted lines in Fig. 2, and also in Fig. 3, has a central solid portion 9 of smaller diameter than the diameter of the cylinder and with radiating and downwardly bent

arms 10. These arms 10 are extended down preferably on the interior of the measuring cup 5 and are secured to the cup by any suitable means, such as by welding, brazing, soldering, or riveting. The top of the measuring cup or cylinder is thus open around its inner edge which not only makes the structure lighter in weight, but makes it possible to easily keep the device clean and sanitary. Arranged at one side of the sleeve 7 is a handle 11, whereby the device may be manipulated. This handle is preferably made of a piece of metal folded upon itself with sufficient space between the folds to provide a firm grasp. The ends of the handle are bent 55 at right angles and secured to the sleeve by any suitable means.

Mounted within the cylinder 5 is an ejector disc 15 which is slightly less in diameter than the interior diameter of the cylinder 5 so that it may have free movement therein. The disc is provided with a number of upstanding tabs 16 which engage the interior of the cylinder and serve to guide the disc. These tabs also serve to guide the disc and retain it in 60 registering position with the cylinder when it is moved to its lowermost position, in which position it is some distance below the lower edge of the cylinder. This provision is made so that there will be a free and unobstructed space for the discharge of water in 65 which it is customary to keep such devices when not in use. This provision also aids in keeping the device clean and sanitary.

The disc 15 is carried by an ejector rod 20 which is slidably mounted within the sleeve 7. This ejector rod is preferably semi-circular in cross-section having its curved surface in contact with one side of the sleeve. The lower end 21 of the rod is bent at right 70 angles and secured to the disc by any suitable means.

The device is provided with an ejector knob 22 which is carried by screw 23. This screw passes through a longitudinal slot 24 formed in the sleeve 7 and into the upper end of the ejector rod 20. By manipulating the ejector handle, the ejector disc 15 may be raised and lowered. The bottom end of the slot 24 is so positioned that the disc 15 will 75

be stopped in its downward movement when it reaches the position shown in the drawings. The upper end of the ejector rod 20 extends preferably some distance above the screw 23 and is limited in its upward movement by means of an adjustable stop screw 25. This stop is screw-threaded into the upper end of the sleeve 7, and provides means whereby the predetermined capacity of the measuring cup or cylinder 5 may be adjusted. The slot 24 is preferably formed in the sleeve at a position with relation to the handle 11 in which it will be readily accessible by the thumb of the hand holding and operating the device.

Arranged centrally through the measuring cup or cylinder 5 is a cut-off knife 26. This knife is disposed in the same plane as the plane of the flat surface 27 of the ejector rod 20, and the ejector rod is kept in position by its contact with one of the side faces of the knife. The knife is preferably provided with an upwardly extending tab 28 which enters the bottom end of the sleeve 7 and provides means for holding the knife in position. The lower part of the knife is considerably less in width than the diameter of the measuring cup and its lower edge 29 which is sharpened is disposed on a plane with the lower edge of the cup. A plurality of holes 30 are formed through the knife near the lower end thereof, and these serve to provide additional frictional means for handling ice cream or other delicacies which are not properly frozen.

The ejector disc 15 is, of course, provided through its central portion with a slot 31 which passes over the knife 26 as the ejector disc is raised to its upper position.

When the device is to be used, it is obvious that it is grasped by the handle 11 and forced into the bulk of ice cream from which a measured quantity is to be dispensed. As the measuring cup is forced down into the ice cream, the ejector disc 15 will, of course, be forced upwardly within the cylinder until the upper end of the ejector rod 20 reaches the stop screw 25. The cylinder has now been completely filled with ice cream and before withdrawing the same from the bulk, the device is rotated without moving it axially, and such rotative movement serves to sever the ice cream over the area which is thus covered by the lower edge of the knife 26. The portion of the cylinder of ice cream contained within the measuring cup which lies between the side edges of the knife 26 and the interior of the cylinder are relatively thin, and, therefore, easily break from the bulk of the cream. The device is now raised from the container by means of the handle and it is ready to be dispensed either in a dish for immediate service or into a carton. When it is to be dispensed, the thumb of the hand holding the device is pressed down upon the

handle 22 which serves to force the ejector disc 15 downwardly and thus eject the ice cream content of the cup. If it is found that the measure of the cup is not accurate, the measured contents may be adjusted by moving the stop screw 25.

Obviously, some modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A dispensing device comprising a measuring cylinder, a hollow sleeve carried by the cylinder, an ejector disc mounted within the cylinder and carried by an ejector rod movable within the sleeve, and a stationary cut-off knife carried by and located within the cylinder and extending across the center of the cylinder for a major portion of its diameter, the ejector disc being formed with a slot for passage over the knife.

2. A dispensing device comprising a measuring cylinder, a hollow sleeve carried by the cylinder, an ejector disc mounted within the cylinder and carried by an ejector rod movable within the sleeve, the ejector disc having upwardly extending tabs engaging with the wall of the measuring cup, and a cut-off knife located within the cylinder and extending across the center of the cylinder for a major portion of its diameter.

3. A dispensing device comprising a measuring cylinder, a hollow sleeve carried by the cylinder, an ejector disc mounted within the cylinder and carried by an ejector rod movable within the sleeve, and a cut-off knife carried by the sleeve and extending across the center of the measuring cup for a major portion of its diameter, the knife being provided near its lower end with a plurality of apertures.

4. A dispensing device comprising a measuring cylinder having an open top, a hollow sleeve carried by the top, a handle carried by the sleeve and arranged at right angle thereto, an ejector disc slidably mounted within the cylinder, an ejector rod carried by the disc and disposed within the sleeve, the sleeve being formed with a longitudinal slot, and a handle engaging the rod passing through the slot, and a stationary cut-off knife centrally located within and carried by the cylinder, the knife passing through a slot formed in the disc.

5. A dispensing device comprising a measuring cylinder, a hollow sleeve carried by the cylinder, an ejector disc mounted within the cylinder and carried by an ejector rod movable within the sleeve, a stationary cut-off knife carried by and located within the cyl-

inder and extending across the center of the cylinder for a major portion of its diameter, the ejector disc being formed with a slot for passage over the knife and an adjusting stop screw carried at the upper end of the sleeve and engageable with the upper end of the ejector rod.

5 In testimony whereof, I have hereunto signed my name.

10
